(57) **CLAIM**

The ornamental design for an electronic vaping device, as
shown and described.

DESCRIPTION

FIG. 1 is a front perspective view of an electronic vaping
device;

FIG. 2 is a rear perspective view of the electronic vaping
device of FIG. 1;

FIG. 3 is a front elevation view of the electronic vaping
device of FIG. 1;

FIG. 4 is a rear elevation view of the electronic vaping
device of FIG. 1;

FIG. 5 is a left side elevation view of the electronic vaping
device of FIG. 1;

FIG. 6 is a right side elevation view of the electronic vaping
device of FIG. 1;

FIG. 7 is a top plan view of the electronic vaping device of
FIG. 1; and,

FIG. 8 is a bottom plan view of the electronic vaping device
of FIG. 1.

The broken lines in the drawings depict portions of the
electronic vaping device that form no part of the claimed
design.
